UNITED STATES PATENT OFFICE.

JASON L. MERRILL, OF WASHINGTON, DISTRICT OF COLUMBIA.

PROCESS OF MANUFACTURING TOW FROM FLAX AND SIMILAR PLANTS.

1,222,968.

Specification of Letters Patent. Patented Apr. 17, 1917.

No Drawing.

Application filed February 26, 1917. Serial No. 151,121.

(DEDICATED TO THE PUBLIC.)

To all whom it may concern:

Be it known that I, JASON L. MERRILL, a citizen of the United States of America, and an employee of the Department of Agriculture of the said United States, residing at Washington, District of Columbia, (whose post-office address is Washington, District of Columbia,) have invented a new and useful Process of Manufacturing Tow from 10 Flax and Similar Plants.

This application is made under the act of March 3, 1883, chapter 143 (22 Stat., 625), and the invention herein described and claimed may be used by the Government of 15 the United States or any of its officers or employees in the prosecution of work for the Government, or any person in the United States, without payment to me of any royalty thereon.

20 My invention relates to improvements in the process of manufacturing tow, whereby the tow shall contain such a low proportion of woody matter that said tow may be used economically in the manufacture of paper.

25 The stem and branches of the flax plant consist of an inner hollow cylindrical core of woody matter surrounded by a thin layer of bark in which occur the true flax fibers.

Processes are in commercial operation by 30 which layers of flax straw are broken by means of corrugated crushing rollers and much of the woody matter is removed but not enough of the woody matter is removed to render the tow suitable for the economic- 35 cal manufacture of paper of suitable quality.

Processes have been devised wherein a layer of flax straw is repeatedly crushed or broken by being rolled successively through a series of corrugated rolls operating in 40 pairs, the layer of straw being conveyed automatically from each pair of rollers into the succeeding pairs.

In many processes the layer of straw is stretched or drawn in the direction of its 45 movement while passing through a series of crushing rollers but the extent of this stretching or drawing is slight, being little more than sufficient to maintain the layer of

straw taut in the direction of its movement through the series of crushing rollers. 50

My process consists in breaking a layer of the straw by transversely bending it in a multiplicity of places in such manner that the central woody portion shall be broken into more or less fine pieces or sections and subsequently subjecting the broken layer of straw to a violent pulling or drawing action of such intensity that the layer is either pulled apart or reduced to a very thin layer, 60 during which action the fibrous constituents of the straw are drawn over each other, thereby loosening the adhering fine pieces of woody matter. During both of these actions more or less fine woody matter falls away from the layer of straw and the remaining fine woody pieces may be removed subsequently by means of the various well known dusting processes. 65

This action may be secured by any construction of machine, but I prefer to use a 70 series of pairs of rollers, corrugated or fluted longitudinally, in which series the alternate pairs of rollers have a peripheral speed approximately five times the peripheral speed of the other pairs of rollers. The difference in peripheral speeds may be any ratio provided that it creates a violent pulling or drawing action on the layer of broken straw. 75

This process is applicable to threshed flax straw of the seed-variety and if such straw 80 is retted it will yield a tow containing less woody matter than if unretted.

From the foregoing, it is thought that the operation and many advantages of the herein described process will be apparent to 85 those skilled in the art, without further description, and it will be understood that various changes and variations may be resorted to in practising the process without departing from the spirit or sacrificing any 90 of the advantages of the process.

Having thus described my invention, I claim:

A process for the manufacture of tow from flax and similar plants, consisting in 95 breaking fibrous material in a multiplicity

of places by subjecting the material to transverse bending, then subjecting the bended material to violent pulling and simultaneously therewith drawing the fibrous constituents of the material over each other for effecting the removal of the fragmentary woody substances adhering thereto, substantially as specified.

In testimony whereof, I affix my signature in the presence of two subscribing witnesses. 10

JASON L. MERRILL.

Witnesses:

CHARLES W. BOYLE,
THOMAS SHAW.
